Primary Examiner — Thomas Johannes*Assistant Examiner* — April Rivas(74) *Attorney, Agent, or Firm* — Banner & Witcoff, Ltd.

CLAIM

The ornamental design for a cooler, as shown and described.

DESCRIPTION

FIG. 1 is a top, front, right perspective view of a cooler showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the drawings illustrate portions of the cooler and form no part of the claimed design.

1 Claim, 6 Drawing Sheets# US D830,134 S
